UNITED STATES PATENT OFFICE.

ALBERT SCHINKEZ, OF GRAND HAVEN, MICHIGAN, ASSIGNOR TO WILLIAM H. KELLER, INC., OF GRAND HAVEN, MICHIGAN, A CORPORATION OF MICHIGAN.

ROTARY PISTON DRILL.

Application filed December 16, 1920. Serial No. 431,129.

To all whom it may concern:

Be it known that I, ALBERT SCHINKEZ, a former subject of the Emperor of Austria, residing at Grand Haven, in the county of Ottawa and State of Michigan, have invented certain new and useful Improvements in Rotary Piston Drills, of which the following is a specification.

The invention relates to a pressure fluid actuated tool and especially to a tool of this general class having a spindle or shaft to be driven, such, for example, as a pneumatic drill; and this application is a continuation in part of my copending application Serial No. 369,180 filed March 29, 1920.

The general object of the invention is to provide an exceedingly practical tool of the character stated, embodying the principle of operation wherein the actuation of the tool spindle is accomplished by a plurality of pistons mounted in a rotatable element and acting upon a relatively inclined member to effect the rotation thereof with the rotatable element, the member being operatively associated with the spindle.

The object of the invention more specifically stated is to provide a construction and arrangement of the tool parts such as will result in a tool of an exceedingly compact character, of light weight, of substantial durability, and of high efficiency in operation.

A further object of the invention is to produce a tool which is capable of being quickly and easily disassembled and reassembled for convenience in making repairs and in the renewal of parts.

The objects of the invention thus generally stated, together with other and ancillary advantages which will be apparent as the description proceeds, are attained by the construction and arrangement illustrated in the accompanying drawings forming part hereof in which Figure 1 is a longitudinal central sectional view through a tool embodying the features of my invention. Fig. 2 is a transverse sectional view through the tool taken substantially in the plane of line 2 of Fig. 1. Figs. 3 and 4 are similar views taken respectively substantially in the planes of lines 3 and 4 of Fig. 1, the pistons being omitted from Fig. 3. Fig. 5 is a perspective view of a part of the pressure fluid distributing means, detached. Fig. 6 is a similar view of another part of

said means. Fig. 7 is a perspective view of a gear element operatively connecting certain parts of the tool in their rotation.

The tool comprises generally a casing 8 having a hand portion 9 connected with the rear end wall of the casing by means of a neck portion 10. In the forward end of the casing is journaled a tool spindle 11 having a direct gearing connection with a rotary element 12. Said element embodies a plurality of cylinders each having a piston reciprocable therein and connected with an inclined rotatable element 13, and the element 12 is operatively associated with said element 13 so that the two elements rotate in unison. Means for controlling the flow of pressure fluid to the cylinders of the element 12 to effect their operation includes a distributor comprising a stationary section 14; also a movable section 15 operable in the rotation of the element 12 to permit of the admission and exhaust of pressure fluid from the cylinders in succession.

The casing 8 is made annular in form and of relatively short length, forming in effect a barrel, and is constructed in two sections 8^a and 8^b secured together in any suitable way. Preferably the rear section 8^a and the handle are formed integral, the rear end wall of the casing having a rearward extension 10^a into which the neck portion 10 of the handle merges. The section 8^b carries a journal bearing 16 for the shank 17 of the spindle 11.

The hand portion 9 of the tool embodies the usual valve means 18 manually operable through the medium of a lever 19 to control the flow of pressure fluid to the distributing means by way of a passageway 20 which extends through the neck portion 10 of the handle and the extension 10^a of the casing.

The tool spindle 11 has keyed upon its rear end a spur gear 21 having an operative connection with a gear element 22 having a stem 23 at its forward end journaled in the forward wall of the casing. Preferably, a journal bearing 24, of suitable metal, for said stem 23 is secured in position in the front wall of the casing. The gear element 22 embodies a spur pinion having its teeth 25 formed in an enlarged portion of the element and meshing with the pinion 21.

At its rear end, the gear element 22 has a non-rotative quick detachable clutch con-

nection with the piston element 12. The latter element (Fig. 3) comprises a plurality of cylinders 26 preferably cast integral with each other and with a central bearing sleeve 27 which is mounted for rotation on the stationary section 14 of the distributing means mounted in the rear wall of the tool casing as will be more fully described hereinafter. For this purpose, said section 14 has a forwardly projecting stem or journal member 28 between which and the central bearing sleeve 27 of the element 12 may be interposed a bushing 29 of suitable bearing metal. Into the forward end of said sleeve 27 projects a stud 30 integral with the gear element 22, and the extreme forward end of said sleeve is recessed at diametrically opposite sides as shown at 31 (Fig. 3) to receive the opposite ends of a head or block 32 (Figs. 1 and 7) also rigid with the gear element, the stud 30 extending rearwardly from said block. By this means, the piston element 12 is rigidly connected with the gear element 22 so that the elements are nonrotatable with reference to each other but capable of quick and easy detachment.

The inclined rotatable element 13 is in the form of an annular or ring member 33 mounted to rotate in a bearing member 34 stationarily mounted in the forward portion of the casing. The lower portion of said bearing member 34 has a seat 35 in the forward wall of the casing and the upper and side portions of the member are seated in an inwardly projecting portion 36 of the casing between the sections 8^a and 8^b thereof. Preferably ball bearings 37 are interposed between the ring member 33 and its bearing 34, the balls being retained in position by means of a suitable retainer 38.

Each of the cylinders 26 of the element 12 has mounted therein a piston 39, and the pistons are connected by means of pitmen 40 with the ring member 33, the opposite ends of the pitmen having universal connections with the pistons and the ring member. For securing in position the ball members comprising the universal connections at the forward ends of the pitmen, the ring member 33 has formed therein a plurality of sockets 41 one for each of the ball members, and the ball members are secured in position in their sockets by means of a retaining ring 42 secured in position as by means of screws 43 (Fig. 2) and having suitable apertures 41^a for the reception of said ball members. Preferably the ring is provided upon the outer sides of said apertures with slots 42^a adapted to pass the pitmen in the assembling of the parts.

The ring member 33 of the inclined element has a gearing connection with the gear element 22 and hence with the spindle 11, by means of a bevel gear ring 44 rigidly secured within the member 33 as by being

pressed thereinto and having teeth meshing with a bevel gear pinion 45 rigid with the gear element 22. The gear ring 44 and pinion 45 have the same number of teeth so that the elements 12, 13 and 22 operate in unison. It will be observed that the gear element 22 being fixed with reference to the piston element 12, and geared directly to the inclined element 13, there is provided, in effect, a universal connection between these elements which serves effectively to maintain at all times these parts in proper alinement. Moreover, this element 22, because of its connections with the elements 12 and 13, constitutes a driving shaft for the tool spindle or other element to be driven, which is arranged coaxially of the piston element 12 and passes through the inclined element 13, thus lending extreme compactness to the tool.

The stationary section 14 of the distributing means for the pressure fluid, comprises an elongated cylindrical member 46 extending coaxially of the casing through the rearward extension 10^a and having at its rear end a screw-threaded stud 47 adapted to receive a nut 48 by means of which the member is rigidly secured in the rear end of the casing. At its forward end, said member 46 carries the journal member 28 upon which the element 12 is rotatably mounted. Upon opposite sides the cylindrical member 46 is recessed to form respectively an inlet chamber 49 and an exhaust chamber 50 (Figs. 1, 4 and 5). The inlet chamber 49 communicates by way of a duct 51 with the passageway 20 which leads to the source of pressure fluid supply. The chamber 50, on the other hand, communicates by way of a duct 52 with a downwardly extending exhaust port 53 formed in the rear wall extension 10^a of the casing.

The section 15 of the pressure fluid distributing means comprises a sleeve 54 (Fig. 6) rotatably mounted upon the member 46 of the distributor section 15 and fixed within a rearwardly projecting tubular stem formed by an annular flange 55 formed on the element 12. At equidistantly spaced points in the periphery of the sleeve 54 are formed a plurality of recesses 56. These recesses, together with the stem 55, form passageways opening at their forward ends into the rear ends of the cylinders 26 as by way of ports 57 (Fig. 3), and communicating at their rear ends with the chambers 49 and 50 in the rotation of the sleeve, as by way of slots 58.

Preferably, I employ four cylinders 26 equidistantly arranged about the axis of the tool, and for each of the cylinders there is provided in the sleeve 54 a recess 56 having a slot 58. It will be apparent that in the rotation of the sleeve with the cylinders 26 communication is established alternately be-

tween the inlet chamber 49 and the cylinders, and between the exhaust chamber 50 and said cylinders. In this operation, the member 46 of the stationary distributer section 5 acts as a valve member to control the slots 58 so that the pistons are driven forwardly in succession, while the cylinders exhaust in succession in the rearward movements of the pistons.

10 The pistons of the element 12 when thus actuated by the admission and exhaust of pressure fluid under the control of the distributing means, act upon the inclined element 13 to impart rotation thereto, and 15 the latter drives the gear element 22 through the gearing connection 44, 45. The gear element in turn drives the spindle 11 through the gearing connection 21, 25.

A thrust bearing 59 of suitable construction is preferably interposed between the rotary element 12 and the rear wall of the casing, and may advantageously be arranged so as to encircle the annular flange 55, fitting neatly thereover.

25 When it is desired to disassemble the tool for any reason, as for the purpose of making repairs, it is only necessary to disconnect the section 8^b from the section 8^a by removing its securing screws (not shown). The piston element, it will be observed, is readily withdrawable out of the casing section 8^a, and is capable of being freely disconnected from the elements 13 and 22, the pistons being withdrawn from their respective cylinders and the clutch connection 31, 32 disengaged in this operation.

It will be observed that I have provided a tool of extreme simplicity, and one of a practical character. The tool as a whole is 40 of relatively light weight construction, and the parts are arranged with great compactness. The tool is thus capable of use in relatively restricted places and may be conveniently handled by the workmen. Moreover,

by reason of the fact that the rotating piston and inclined elements encircle the central drive shaft the tool may, in case of the larger models, be readily equipped with a feed screw extending centrally through the casing unrestricted by said elements.

45 The operative connection through the gear element 22 between the several rotative elements of the tool is of especial importance by reason of the effective manner in which these elements are maintained in proper operative association with a minimum consumption of power by friction in operation.

50 The foregoing illustrates one embodiment only of my invention but it is to be understood that changes may be made in the form, arrangement and construction of the various novel features; that their mode of operation may be varied and that features may be omitted without departing from the spirit and scope of the invention.

55 I claim as my invention:

A pressure-fluid-actuated tool comprising, in combination, a casing, a rotary element providing a plurality of circumferentially arranged cylinders rotatably mounted as a 60 unit in said casing and each having a piston therein, a tool spindle journaled in the casing, a rotary inclined member operatively connected with said pistons and with said spindle, said connection being adapted to 65 maintain the member and cylinders in rotative alinement and comprising a gear element journaled at its forward end in the casing and fixed at its rear end in said rotary element, said gear element having a 70 spur pinion and a bevel pinion, said tool spindle having a spur gear adapted to mesh with said spur pinion, and said annular member having bevel gear teeth meshing with said bevel pinion.

75 In testimony whereof, I have hereunto set my hand.

ALBERT SCHINKEZ.
